(57) **CLAIM**

The ornamental design for a ground anchor handle, as shown and described.

DESCRIPTION

FIG. 1 is a top isometric view of a ground anchor handle; FIG. 2 is a front side view of the ground anchor handle in FIG. 1;

FIG. 3 is a back side view of the ground anchor handle in FIG. 1;

FIG. 4 is a left side view of the ground anchor handle in FIG. 1;

FIG. 5 is a right side view of the ground anchor handle in FIG. 1;

FIG. 6 is a top view of the ground anchor handle in FIG. 1; and,

FIG. 7 is a bottom view of the ground anchor handle in FIG. 1.

The broken lines in the figures show portions of the ground anchor handle that form no part of the claimed design.

1 Claim, 4 Drawing Sheets
